UNITED STATES PATENT OFFICE.

RODOLPHUS FULLER, OF DETROIT, MICHIGAN.

RHEOSTAT-SWITCH.

SPECIFICATION forming part of Letters Patent No. 650,582, dated May 29, 1900.

Application filed October 27, 1899. Serial No. 734,936. (No model.)

To all whom it may concern:

Be it known that I, RODOLPHUS FULLER, a citizen of the United States of America, residing at Detroit, in the county of Wayne 5 and State of Michigan, have invented certain new and useful Improvements in Rheostat-Switches, of which the following is a specification, reference being had therein to the accompanying drawings.

10 This invention relates to that kind of rheostat-switch in which a pivoted contact-arm coöperates with a series of fixed contacts to cut the resistance out or introduce it into the motor-circuit by moving the contact-arm over 15 the fixed contacts in starting and stopping the motor.

My invention consists in the peculiar construction and arrangement of parts whereby 20 the switch operates automatically as a safety and limit switch, whereby the contact-arm returns automatically to its starting position and opens the circuit of the motor upon a failure of the current or if the same should exceed a predetermined maximum, all as more 25 fully hereinafter described, and shown in the accompanying drawings, in which—

Figure 1 is a face view of my rheostat-switch, showing it as it appears fastened in position to a vertical wall. Fig. 2 is a plan as 30 it appears looking at it from the under side. Fig. 3 is a section on line $x-x$, Fig. 1. Fig. 4 is a face view similar to Fig. 1 and showing in diagram the electrical circuits.

A is a box in which the resistance-coils are 35 inclosed. B is the cover of the box, made of slat or other insulating material. C is the pivoted contact-arm. D represents the fixed contacts to which the terminals of the resistance-coils are connected. D' is the dead-contact 40 at the starting-point. E and F are stops limiting the movement of the contact-lever. G is the pivot of the contact-lever. H is a spring inclosed in the hub c of the contact-lever and operating by its tension to move the contact-lever into the starting position when released. 45 I is a contact-spring secured to the contact-lever, and J J' are binding-posts, all the aforementioned parts being of known construction and operation.

50 My invention consists in the combination, with the above parts, of a combined retaining and releasing magnet K, which is connected

into the motor-circuit and has two pole-pieces a a, connected to opposite ends of the core, and two independent armatures L and M, 55 adapted to contact therewith.

The armature L is for retaining the contact-arm in any position to which it may be adjusted. It is provided with a split hub b, sleeved upon the hub c of the contact-arm, 60 and a clamping-screw d passes through the split ends for the purpose of clamping the armature upon the hub of the contact-arm to operate in the manner more fully hereinafter described. 65

The armature M is pivoted on the under side of the pole-pieces of the magnet, so that gravity will tend to hold it out of contact therewith. Its free end projects through a slotted guide e, which carries an adjusting-screw f, by means of which its proximity to the opposite pole of the magnet may be adjusted, a suitable index being preferably engraved on the guide. 70

To the free end of the armature M is secured a contact-spring g, which is adapted to press against two fixed contacts h h' when the armature is closed upon the poles of the magnet, and these two fixed contacts are open terminals of a short circuit around the magnet. 75

For a better understanding of the operation of my device I show in Fig. 4 the electrical connections, in which N represents the source of electricity, and O the motor controlled by the device. From the generator the current 80 passes through conductor 1, binding-post J', conductor 2, contact h', conductor 3, coil of magnet K, conductor 4, contact h, conductor 5, pivot G, flange p of pivot, contact-spring I, the contact D upon which the contact-arm 85 rests, conductor 6, binding-post J, conductor 7, field-coils and armature-coils of motor, and conductor 8 to source of electricity, thus completing the circuit in the position of the parts shown in Fig. 4, which is the position when 90 the motor is in normal operation. When the motor is at rest, the contact-arm is on the dead-contact D', as in Fig. 1, the circuit of the motor is open, and the magnet K is not energized. In starting the motor the contact-arm 95 is gradually moved over the contacts D, which closes the motor-circuit first through the whole resistance and thence cutting the same out step by step in the usual manner. The 100

armature L, being frictionally clamped upon the hub of the contact-arm, moves with the contact-arm until it rests against the poles of the magnet, which, being energized, holds it there, and with it the contact-arm, which otherwise would return to its original position. As long as the magnet remains energized the armature L is thus adapted to hold the contact-arm in any position into which it may have been moved from its initial position, provided the armature is brought into contact with the poles of the magnet, which may be done by the hand of the operator independently of any movement of the contact-arm. Upon a failure of current from any cause whatever the magnet K would cease to hold the armature and allow the spring H to automatically retract the contact-arm to its starting position. The same would occur if the current exceeds a certain maximum, which increases the magnetic strength of the magnet to cause it to attract the armature M and close the circuit around the magnet through the fixed contacts h h', thereby energizing the magnet and causing the contact-arm to fly back into its starting position again.

The set-screw f serves to regulate the amount of air-gap between the poles a and the armature M, as required to operate at a current of any given maximum strength, as shown on the index.

To prevent the armature L from sticking to the poles of the magnet, I preferably insert a small copper pin k into the outer pole, which projects just a trifle beyond the pole to keep the armature out of direct contact.

I am aware that rheostat-switches have been devised heretofore which are intended to accomplish the same results; but they are more complicated and embody usually two or more magnets, while I have but one magnet with a single coil operating both as a retaining and as a releasing magnet. Further, I dispense with intervening mechanism between the armatures and the contact-arm, (the armature L being virtually a part of the contact-arm,) and as a result of my construction the contact-arm is never positively locked in any position, and thus in an emergency it can be instantly turned to open the circuit of the motor.

What I claim as my invention is—

1. In a rheostat-switch for electric motor, the combination with the pivoted contact-arm adapted to close the circuit of the motor and having a retracting device to automatically

return it to its starting position and open the circuit when released, of an electromagnet in the circuit of said motor, a retaining-arm pivotally mounted upon the contact-arm and adapted to constitute an armature and be held in position by said electromagnet independent of the position or movement of the contact-arm, and a friction device interposed between said retaining-arm and the contact-arm.

2. In a rheostat-switch for electric motor, the pivoted contact-arm thereof having a hub, a retracting-spring inclosed within said hub and a retaining-arm pivotally clamped upon said hub and having a frictional resistance thereon exceeding the power of the retracting-spring and adapted to permit a relative movement between said contact-arm and the retaining-arm in operating the switch.

3. In a rheostat-switch for electric motor, the combination with a series of fixed contacts and a pivoted contact-arm having a retracting-spring to automatically open the circuit when released, a retaining-arm pivotally clamped upon the hub of the contact-arm independently movable thereon and adapted to hold the same in position independently movable of said retaining-arm, and an electromagnet in the circuit of the motor having pole-pieces, adapted to be magnetically connected by said retaining-arm and hold the same in position when the electromagnet is energized.

4. In a rheostat-switch for electric motor, the combination with the pivoted contact-arm adapted to close the circuit of the motor and having a retracting device to automatically return it to its starting position and open the circuit of the motor when released, a retaining-arm pivotally clamped upon a hub on the contact-arm and adapted to hold the same in position independently movable thereon, an electromagnet in the circuit of the motor having pole-pieces adapted to be magnetically connected by said retaining-arm to hold the same in position, and an armature adapted to co-operate with said electromagnet independent of the retaining-arm and adapted to short-circuit the same, at the maximum current strength the motor is designed to carry.

In testimony whereof I affix my signature in presence of two witnesses.

RODOLPHUS FULLER.
